UNITED STATES PATENT OFFICE.

LEO W. SCHLEICHER, OF DETROIT, MICHIGAN.

TOOL HANDLE.

Application filed July 2, 1926, Serial No. 120,013.

This invention aims to provide a tool handle wherein the tangs or shanks of tools, such as files, engravers' tools, screwdrivers, and the like may be positively held without fear of the tool and handle accidentally coming apart when in use.

Another object of the invention is to provide a guide which is a sliding fit into the bore of the handle and has a passage through it for the tang or shank of the tool to pass through, so that the same handle may be used in combination with different guides having passages of various sizes and shapes to accommodate different sorts of tangs or shanks.

A further object of the invention is to provide a tool handle wherein means are arranged for holding tools longitudinally out of alignment with the handle, since a tool so held can sometimes be advantageously used.

Having thus briefly outlined the major purposes of the invention I will now proceed to describe two embodiments thereof with the aid of the accompanying drawings.

Figure 1 illustrates the tool handle and a file held thereby.

Figure 2 is a longitudinal section of the invention.

Figure 3 is a section on the line III—III of Figure 2.

Figure 4 is a section on the line IV—IV of Figure 2.

Figure 5 shows a slightly modified form of construction of the invention wherein the tool is also held out of alignment with the handle.

Referring first to Figures 1 to 4, 1 designates a handle having a longitudinal bore 2 extending from one of its ends for a considerable portion of its length. An annular band 3 is arranged around the open end of the handle. Through the band and handle is a transverse slot 4 usually tapered to receive a correspondingly tapered locking member 5 through which latter an opening 6 is provided.

A removable guide 7 is inserted in the bore 2 and has a collar 8 integral with it which bears against the open end of the handle. Through the guide is a passage 9 of such size and shape as to fit around the tang or shank 10 of the tool 11 to which it is intended to secure the handle. The inner end 12 of the guide is a push fit into the bore 2.

The tang 11 extends through the guide 7 and projects into, and usually through, the opening 6 in the locking member 5. 15 indicates a countersunk head set screw threaded through the locking member which bears against the side of the tang 11 and holds it firmly in the handle. As shown in Figure 4 the opening through the locking member is preferably flat on the side opposite the one through which the set screw 15 projects, so as to afford a bearing surface against which the tang 11 may be held. Moreover the opening may also be made taper if desired to suit the taper of the tang of the tool.

In practice I find that two or at most three guides 7 having passages 9 of different shapes and sizes are ample for holding a wide range of tools having different forms and sizes and tangs. In fact if only one guide having a large passage through it is provided the fact that the tang is a very poor fit in the guide will, in most cases, not impair the utility of the handle because the grip of the set screw on the tang, and the bearing of the latter against one side of the opening 6, is usually sufficient to hold the tool and handle securely together.

In Figure 5 a slightly modified construction is shown wherein the handle 1^a terminates at the inner end of the guide 7^a and the latter fits into the band 3^a which projects beyond the handle. In this case the end of the band 3^a forms the stop against which the inner end of the collar 8^a bears. It will also be noted that the band 3^a is beaded as shown at 3^b to hold it firmly on the handle.

The passage 9^a through the guide 7^a is made slightly larger than the tang of the tool it is to accommodate, and the opening 6^a through the locking member 5^a is wider than the tang. Two set screws 15^a are provided from opposite sides of the locking member so that by varying their adjustment the tool can be securely held at varying angles out of alignment with the handle.

It is understood that the constructions herein described are, however, subject to such modifications as fall within the scope of the appended claims.

What I claim as my invention and desire to secure by Letters Patent is:

1. In a tool handle, the combination of a handle having a bore extending longitudinally from one end, said handle having a

transverse slot therethrough, a locking member in said slot having an opening through it of lesser cross section than said bore and registering with said bore, a set screw threaded into said locking member adapted to extend into said opening, and a guide in the outer end of said bore having a collar bearing against the bored end of said handle, said guide having a passage therethrough in alignment with said locking member opening.

2. In a tool handle, the combination of a handle having a bore extending longitudinally from one end, a guide bearing against said bored end and having a portion of lesser cross section extending into said bore,

said guide having a passage therethrough, said handle having a slot transversely therethrough, a band around said handle extending from said bored end past said slot, said band having a passage therethrough registering with said slot, a locking member in said slot having an opening therethrough substantially in line with said guide passage, said locking member having a threaded hole therein extending into said opening and substantially at right angles to the latter, and a screw in said threaded hole adapted to grip the end of a tool inserted through said guide passage into said opening.

LEO W. SCHLEICHER.
